(57) **CLAIM**

The ornamental design for a modular LED light housing for wall mounting, as shown and described.

DESCRIPTION

FIG. 1 is a perspective view of a first embodiment of a modular LED light housing for wall mounting;
FIG. 2 is a front elevational view thereof;
FIG. 3 is a rear elevational view thereof;
FIG. 4 is a left elevational view thereof, a right elevational view being a mirror image thereof;
FIG. 5 is a top plan view thereof; and,
FIG. 6 is a bottom plan view thereof;
FIG. 7 is a perspective view of a second embodiment of a modular LED light housing for wall mounting;
FIG. 8 is a front elevational view thereof;
FIG. 9 is a rear elevational view thereof;
FIG. 10 is a left elevational view thereof, a right elevational view being a mirror image thereof;
FIG. 11 is a top plan view thereof; and,
FIG. 12 is a bottom plan view thereof.
